Gleason Works, Rochester, N. Y., a corporation
of New York

Application August 21, 1936, Serial No. 97,248

6 Claims. (Cl. 90—56)

The present invention relates to indexing mechanism and particularly to indexing mechanism of the type employed on machines for producing gears.

5 One object of the present invention is to provide an indexing mechanism which will be substantially noiseless in operation.

A further object of the invention is to provide an index mechanism which is positively actuated 10 and which, therefore, will be less likely to get out of order and will have a longer life than prior types of indexing mechanisms.

Other objects of the invention will be apparent hereinafter from the specification and from 15 the recital of the appended claims.

In the drawings:

Figure 1 is an elevation, with parts in section, of an indexing mechanism embodying the present invention;

20 Figure 2 is a view at right angles to Figure 1, parts being shown in section;

Figure 3 is a fragmentary sectional view on the line 3—3 of Figure 1;

25 Figure 4 is a fragmentary view showing, in plan, the actuating parts of the indexing mechanism;

Figure 5 is a fragmentary sectional view showing details of the cam and lever for operating the index lock-up mechanism, the section 30 through the lever being taken on the line 5—5 of Figure 4; and

35 Figure 6 is a fragmentary sectional view of the cam and the lever for operating the mechanism for rotating the index plate, the section 35 through the lever being taken on the line 6—6 of Figure 4.

The indexing mechanism of the present invention is of the notched plate type and is particularly adapted for use on gear roughing and gear 40 finishing machines in which the cutting operation is performed without a generating roll.

In the drawings, 10 denotes the work head of the gear cutting machine and 11 the work spindle which is suitably journaled in the work head.

45 The machine may be of usual construction save for the indexing mechanism and may have, as shown, a draw-bar 7 for operating the work chucking mechanism, a spring 8 for actuating this draw-bar to chucking position and a fluid pressure operated piston 9 for releasing the same.

The indexing mechanism itself will now be described.

12 denotes the index plate which is keyed to the work spindle and secured against a shoulder 55 on the spindle by the nut 13. 15 designates the

guard or housing for the index mechanism. This may be secured to the work head in any suitable manner. The index-plate has a plurality of notches 14.

Pivotaly mounted upon a pin 20 in the guard 5 15 is a lever 21. Secured to this lever by screws 22 is a locking dog 23 which is adapted to engage in the notches of the index plate 12 to hold the work spindle against rotation during cutting 10 of the gear teeth.

25 denotes an arm which is rotatably mounted upon the work spindle 11 by means of its hub 26. Pivotaly mounted upon this arm by means of a pin 28 is a pawl 29.

The pawl 29 is adapted to engage in the notches 15 14 of the index plate 12 to rotate the index plate when the locking dog 23 is in inoperative position. The pawl is constantly urged towards operative position by a spring-pressed plunger 30 which is housed in a recess in the arm 25 and 20 which is adapted to engage the tail 31 of the pawl. The pawl 29 is held out of engagement with the index plate, as long as the locking dog 23 is in operative position by a cam-plate 34 which is secured to the lever 21 by screws 32 and which 25 is adapted to engage roller 33 that is carried by the pawl 29.

The locking dog 23 is moved to and from operating position by oscillation of a crank 35 (Fig. 3). The lever 21 is pivotally connected by means 30 of the pin 36 to a hollow sleeve 37. Slidably mounted in this sleeve is a plunger or rod 38 which is threaded at its lower end for adjustable engagement with a link member 40. The link member 40 is rotatably mounted by means of 35 bushing 41 upon the pin 42 of the crank 35.

The plunger 38 is provided with an enlarged head 44 at its upper end and between this head and a nut 45 which is threaded into the sleeve 37, there is interposed a coil-spring 46. The tension of this spring can be adjusted by rotation at the plunger 38 to thread it further into or out of the link member 40. The lock-nut 47 serves to hold the plunger in any adjusted position.

The crank 35 is oscillated to lift the locking dog 45 23 out of engagement with the index plate 12 to permit of indexing the work spindle, or to return the locking dog to operative position, when indexing has been completed, by operation of a cam which forms one track 50 of a double track cam 50 member 51. There is a roller 52 which engages in the cam-track 50. This roller is mounted upon a pin 58 which is secured in a hole in the lever 53 by clamping blocks 59. The lever 53 is fulcrumed upon a pin 54 that is secured by the 55

dowel-pin 55 and screw 56 to a plate 51. The lever 53 is connected at its free end to a bar 60, the connection being by means of the pin 61.

There is a rack 62 secured to the bar 60 by means of screws 63 (Figs. 1, 3, and 4). The rack 62 meshes with a long-faced spur pinion 65 which is keyed to the shaft 66 of the crank 35. The shaft 66 is journaled on anti-friction bearings 67 and 68 in the guard or housing 15.

Through the gearing just described, then, the crank 35 is oscillated to move the locking dog 23 to or from operative position.

When the locking dog 23 is disengaged from the index plate 12, the arm 25 is rotated to cause the pawl 29 to rotate the plate 12 to effect the indexing operation. The hub 26 of the arm 25 is provided with gear teeth forming a segmental spur gear 70. (Figs. 1 and 2.)

The segment 70 meshes with a rack 11 which is secured by screws 72 to a bar 13. The bar 13 slides alongside the bar 60 in a way 15 formed in the bracket 76 and the bar 13 is provided with a tongue 14 at one side which engages in a groove 19 formed in the adjacent side of the bar 60. Thus one bar aids in guiding the other in its movement.

The bracket 76 is secured to the work head or other suitable part of the gear cutting machine by T-bolts 71 (Fig. 2). The plate 51 acts as a cover-plate for the way 15.

The bar 13 is connected at one end by the pin 78 with a lever 80. The lever 80 carries a pin 81 on which is mounted a roller 82 which engages in the cam-track 84 of the cam-member 51. The pin 81 is secured in the lever 80 by clamping blocks 83.

The lever 80 has an adjustable fulcrum. This is formed by the block 85 which slides in the groove 81 in the lever and by the block 88 which slides in a groove 89 formed in the under face of the plate 51 (Fig. 6). There is a pin 90 formed integral with the block 88. This pin engages in a hole in the block 85 and forms a pivotal connection between the block 85 and the block 88. The block 88 is adjustable to control the stroke of the bar 13 by rotation of the screw-shaft 90 which threads into the nut 92, which is secured by a pin (not shown) in the block 90. A taper-gib 94 (Fig. 4) which is adjustable by means of a screw-shaft 95 is provided to clamp the block 85 in any adjusted position.

The cam-member 51 is keyed to a shaft 96 (Fig. 1) which is journaled on anti-friction bearings 97 and 98 in the bracket 76. This shaft may be driven in time with the other operating mechanism of the gear-cutting machine from the shaft 100 (Fig. 2) through the coupling 101, the shaft 102, the bevel gearing 103 and 104, the shaft 105, the worm 106 and the worm wheel 107. The latter is keyed to the shaft 96.

In a gear roughing machine, the cutting tool or tools are alternately fed into the gear blank and withdrawn therefrom. During the feed movement, a tooth space of the blank is cut to full depth and while the tool is withdrawn the blank is indexed. The indexing mechanism of the present invention may readily be employed on any such machine. The indexing mechanism of the present invention may readily be used also on gear finishing machines where a cutter is employed, such as is described in the pending application of J. E. Gleason, Serial No. 711,382 of Feb. 15, 1934. This cutter has a plurality of cutting blades arranged part way around its periphery with a gap between the first and last

blades and the gear blank is indexed once for each revolution of the cutter when the gap in the cutter is abreast of the blank. The indexing mechanism of the present invention may also be employed on gear grinding machines of the type described in the pending application of E. W. Bullock et al., Serial No. 751,738, filed Nov. 6, 1934. Additional uses will occur immediately to those skilled in the art. When the indexing mechanism of the present invention is employed on a gear roughing machine or on a gear grinding machine of the type referred to, it is actuated in time with the feed and withdrawal mechanism of the machine while, when it is employed on a gear finishing machine of the type described, it will be actuated in time with the rotation of the cutter.

In the indexing mechanism of the present invention, the indexing operation is effected by first disengaging the locking dog 23 from the index plate 12, thus permitting the pawl 29 to drop into engagement with the plate. Then the plate is rotated through actuation of the arm 25 to move the plate through an angle sufficient to bring a new notch of the plate into registry with the locking dog. Then the locking dog is reengaged with the plate. The return of the locking dog into engagement with the plate causes the pawl 29 to be disengaged through action of the cam-plate 34. The indexing operation is then complete. The pawl 29 is reset by reverse rotation of the arm 25. The cam-tracks 50 and 84 of the cam-member 51 are so formed as to effect these movements of the locking dog 23 and of the pawl-carrying arm 25 in the described cycle.

Assuming that the parts are in the positions shown in the drawings, the bar 60 is first moved to the right by operation of the cam-track 50 and lever 53 to rotate the crank 40 through operation of the rack 62 and spur pinion 65. The crank raises the rod or plunger 38 which lifts the sleeve 37 and the lever 21 to cause the locking dog 23 to be disengaged from the index plate 12. The plunger moves perhaps $\frac{1}{4}$ " before it engages the upper closed end of the sleeve 37, but thereafter plunger and sleeve move upwardly together.

As soon as the locking dog is disengaged from the index plate, the pawl 29 snaps into engagement with a notch of the plate under actuation of the spring-pressed plunger 30, for, when the lever 21 is lifted the cam-plate 34 is carried clear of the roller 33 on the pawl. The shape of the cam-track 50 of the cam-member 51 is such that at this time, the bar 13 is moved to the right under actuation of the lever 80 and so the arm 25 is rocked counterclockwise to impart indexing rotation to the index plate 12. The amount of rotation of the index plate will depend upon the position of the fulcrum blocks 85 and 88 of the lever 80 and will vary with the number of teeth in the gear being cut.

When the plate 12 has been rotated far enough to bring a new notch into registry with the locking dog 23, the cam-track 50 causes the bar 60 to be moved to the left back to the position shown in Fig. 1. This rotates the crank 40 back to the position shown in this figure, returning the locking dog 23 to locking engagement with the index plate.

As the locking dog returns into engagement with the index plate, the cam-plate 34 contacts the roller 33 of the pawl 29, disengaging the pawl from the index plate. When the locking dog has returned into engagement with the index plate, the index mechanism is reset by operation of the cam-track 84 causing the bar 13 to move back to

the left to the position shown in Fig. 1. This rotates the arm 25 in a clockwise direction to reset the pawl 29.

By adjusting the throw of the lever 80, the work 5 spindle may be rotated different angular distances, when the index plate is unlocked, as is required for different numbers of teeth in the gears to be cut. The index plate used may have the 10 same number of notches as the number of teeth in the gear to be cut or the number of notches may be a multiple of the number of teeth in the gear to be cut.

In prior types of indexing mechanisms of the notched plate type, after the locking dog has 15 been disengaged from the index plate, it is allowed to drop back on the periphery of the plate and it rides on the periphery of the plate, during the indexing rotation of the work spindle, until it registers with the next notch in the plate, when 20 it locks up the index plate again. Since spring-pressure is ordinarily used to return the locking dog to locking position with these prior constructions, the locking dog gets a bump when it drops on to the periphery of the index plate and again 25 when it drops into a notch of the plate. These prior index mechanisms are not only noisy in operation, but with the constant hammering on the index dog, there is a tendency for inaccuracy to creep in and effect the accuracy of indexing. 30 The defects of prior index mechanisms are entirely overcome with the present invention. The locking dog is positively disengaged and positively returned to engagement with the index plate. The locking dog does not ride on the periphery of the index plate until it drops into a 35 notch of the plate, but is returned into engagement with the plate when the work spindle has been rotated far enough to bring a new notch of the plate into registry with the locking dog.

40 In addition, by actuating the plunger 38 through a crank, a slow start and stop movement is imparted to the locking dog so that the locking dog is disengaged from and engaged with the index plate while the plunger is moving at slow speed. 45 This is of especial importance on the locking movement of the dog because, through the crank actuation, the dog is engaged without shock and silently. The coil spring 46 further aids in taking up any shock of reengagement of the locking dog with the index plate.

As a further feature of the invention, it is preferred to form the cam-track 84 so as to impart a slow start and stop movement to the rocker-arm 25. In prior types of index mechanisms, the rocker-arm in its movement first causes disengagement of the locking dog and then rotation of the index plate, so that the indexing pawl is traveling at relatively high speed when it drops into engagement with the index plate and it engages with a shock and some noise. With the mechanism of the present invention, the index pawl is engaged with the index plate before the rocker-arm starts to move. Hence, the index plate starts to rotate at slow speed and 65 without shock or noise. The index mechanism of the present mechanism in all its operations, then, is substantially noiseless and will maintain its accuracy throughout its life.

While the invention has been described in connection with particular embodiment, it will be understood that it is capable of further modification. This application is intended to cover any variations, uses or adaptations of the invention following, in general, the principles of the invention and including such departures from the

present disclosure as come within known or customary practice in the art to which the invention pertains and as may be applied to the essential features hereinbefore set forth and as fall within the limits of the invention or the scope 5 of the appended claims.

Having thus described my invention, what I claim is:

1. In an indexing mechanism, the combination of a rotatable work spindle having a notched index plate fixed thereon, an arm oscillatably mounted on said spindle, a movably mounted dog engageable selectively with the notches of said plate for locking said plate, means including a pawl carried by said arm and engageable with the notches of said plate for rotating said plate, means for holding the pawl out of operative position when the dog is in operative position and means for moving the pawl into operative position when the dog is disengaged, means for positively moving the dog to and from locking position, and means for rotating said arm, when the dog is in inoperative position, to effect indexing.

2. In an indexing mechanism, the combination of a work support, a rotatable work spindle 25 having an index plate fixed thereto, a lever movably mounted on the work support, a locking dog carried by said lever for locking said plate, an arm oscillatably mounted on said spindle, a crank rotatably mounted on the work support, means connecting said crank to said dog to move the dog to and from operative position on oscillation of said crank in different directions, a pawl carried by said arm, means constantly urging said pawl into engagement with said plate, means carried 30 by said lever for preventing such engagement while the locking dog is in engagement with the plate, and means for actuating the crank and arm in timed relation.

3. In an indexing mechanism, the combination 40 of a rotatable work spindle having an index plate fixed thereon, an arm oscillatably mounted on the work spindle, a gear segment secured to said arm, a rack meshing therewith, a movably mounted locking dog for locking the index plate, 45 a crank, means operatively connecting the crank to the dog to move the dog to and from operative position on movement of the crank in opposite directions, a segment operatively connected to the crank, a rack meshing therewith, a pair of 50 cams, means connecting said cams, respectively, to the two racks to reciprocate the racks on rotation of the cams, means adjustable to vary the stroke of the first named rack on rotation of the cam that actuates the same, and means for rotating the cams in timed relation.

4. In an indexing mechanism, the combination of a support, a rotatable work spindle journaled in said support and having a notched index plate fixed thereto, a reciprocably mounted locking dog adapted to engage a notch of the index plate for locking said index mechanism, a crank rotatably mounted on said support, means connecting the crank to said locking dog to move the dog to and from operative position, respectively, 60 on movement of the crank in opposite directions, an arm oscillatably mounted on the spindle, a pawl pivotally mounted on said arm, means constantly urging the pawl into engagement with said notched plate, means preventing engagement 65 of the pawl with the plate when the dog is engaged therewith, means for oscillating the crank and arm in timed relation to first effect withdrawal of the dog and then movement of the arm in one direction to effect indexing rotation of the 70 75

spindle, and means controlling the last named movement of the arm to insure that the pawl is engaged with the index plate before the arm starts to move.

5. In an indexing mechanism, the combination of a support, a rotatable work spindle journaled in said support, a notched index plate fixed thereto, a reciprocably mounted locking dog adapted to engage a notch of the index plate for locking said index mechanism, and means for moving the locking dog to and from operative position comprising a crank, a rod pivotally connected to the crank, a member pivotally connected to the locking dog, means on said member adapted to engage the rod on movement of the rod in one direction to cause the member to move with the rod to disengage the dog from locking position, and resilient means interposed between the rod and member adapted to cushion the return movement of the member and locking dog to locking position under actuation of the rod, means for oscillating the crank, and means for rotating the index plate

relative to the locking dog when the dog is disengaged therefrom to effect indexing.

6. In an indexing mechanism, the combination of a support, a work spindle journaled in the support, a notched index plate fixedly secured thereto, a reciprocably mounted locking dog adapted to engage a notch of the index plate for locking the index mechanism, and means for moving the locking dog to and from operative position comprising a crank, a rod pivotally connected to the crank, a cylinder in which the rod is reciprocable having an end wall against which the rod is adapted to abut when moved in one direction, a coil spring interposed between a head on the rod and the opposite end wall of the cylinder and adapted to hold the locking dog in locking position, and means for oscillating the crank, and means for rotating the index plate relative to the locking dog when the dog is disengaged to effect indexing.

LEONARD O. CARLSEN.
